Signco, Inc., Perrysburg, Ohio, a corporation of
Ohio

Application June 10, 1937, Serial No. 147,436

2 Claims. (Cl. 40—132)

This invention relates to attention-directing displays.

This invention has utility when incorporated in portable signs having collapsible shadow box features therewith.

Referring to the drawing:

Fig. 1 is a front elevation, with parts broken away, of an embodiment of the invention in a unit hereunder;

Fig. 2 is an end elevation from the right of Fig. 1, parts being broken away;

Fig. 3 is a plan view of the device of Fig. 1;

Fig. 4 is a rear elevation of the device of Fig. 1;

Fig. 5 is a view of the blank, say of cardboard, forming the ventilation extension and the back;

Fig. 6 is an elevation of the blank for the frame and wings;

Fig. 7 is a view from the rear of the collapsed assembly of the sign as a unit; and

Fig. 8 is a section on the line VIII—VIII, Fig. 1.

In the operation of the invention hereunder, there is provided a housing or shadow box structure, herein made up of a primary blank having a rectangular frame portion 1 from which are formed triangular cut-out 2 and a pair of slot cut-outs 3. These slot cut-outs 3 are in wings 4 having hinge connections 5 with the rectangular frame portion 1. A cutting 6 severs the wings from the bottom of frame 1. From intermediate the length of this line a cutting 7 extends so that these wings 4 may swing on the hinge portions 5 away from the rectangular frame portion 1. In addition to this frame portion and wing unit blank, there is a cardboard or sheet stock section as a unit having a strip 8 with a hinge 9 assembling integral therewith an extension 10 provided with a hinge connection 11 to a back section 12. In the full assembly hereunder, this strip 8 is joined by an adhesive 13 and wire staples or stitches 14 with an upper edge of the frame 1 along the region of the cut-out 2. In such assembly with the frame 1, the extension 10 will have a taper extent to ride upon the upper edges of the wings 4 in the instance in which the back

12 is a spacer between these wings 4 and has its ears 15 interlocked with the slots 3 for the set up assembly in this open bottom shadow box, in which the lower rear corners of these wings 4 provide the support adjusting portions when the lower side of the frame 1 is resting on a desk, counter or other surface.

Centrally, this back 12 has an opening 16 into which may be inserted socket 17 anchored by rubber friction rings 17'. Such socket is provided with a resistance flasher portion so that electric

conductor lines 18 may cause an incandescent bulb 19 to warm up and then flash intermittently for a display. This rectangular frame 1 is reinforced along one side by the strip 8. The frame 1 is herein shown as about a transparency 20 of glass. This glass in the frame 1 of this display provides or forms a marginal mirror or reflector portion 21. This reflector portion 21 bounds a translucent field 22. There is herein shown in the field 22 a character or letter bounding region 10 23 of reflective or mirror value having intermediate character symbol or body 24, herein shown as a transparency. This transparency 24 may have contrast to differ from the transparency 22 say in color or value for the light as passing 15 therethrough.

This transparency 20 may be assembled with the frame 1 by a sheet metal frame 25 adapted to be snapped into position thereover as to L-sections thereof with an interlocking tongue 26 completing the assembly between the adjoining sections. This sheet metal frame, say of a chrome finish, may give an attractive decorative value to the mirror portion 21 in this portable unit with an appeal markedly departing from the cardboard shadow box characteristics of the attention-effecting display intermittent illumination.

In this strip 8, eyelets or cut-outs 27 are in position so that a hanger or cord 28 may be assembled therewith to permit hanging of this readily-positioned display sign in such a convenient place as might seem appropriate to the one using it for attention direction purposes, whether for attracting attention to a particular merchandise, thing to be done, or other analogous purpose.

This unit is accordingly one wherein the cardboard-like shadow box is readily collapsed by folding the wings 4 against the transparency rear side, thereafter folding the back section 12 toward the hinge 9 with the extension 10 to form 40 the outside of this collapsed shadow box formed from the two cardboard-like sectional units having the integral hinges between the respective sections thereof.

When set up with a light bulb 19 in the shadow 45 box, ports 29 in the extension 10 provide a ventilation draft from the shadow box against heating due to circulation up from a bottom opening or clearance 30.

What is claimed and it is desired to secure by 50 Letters Patent is:

1. A transparency having different opacity degree portions including a bounding section, a trim, and a cardboard-like shadow box assembled by the trim with the transparency, said box em- 55

bodying a frame having a pair of inwardly extending hinge wings and a back for spacing the unfolded wings and having a ventilator extending therefrom anchored with the frame by hinge means in a plane approximating the plane of the hinge for the wings.

2. For a transparency, a cardboard-like shadow box comprising a pair of pieces from flat stock,

one being a frame of rectangular outline integral with cut portions thereof as a pair of wings, the other being a back for spacing the free ends of the wings with a ventilator extension abutting the edge of each wing and anchored with the 5 frame.

CHARLES A. SMITH.
